UNITED STATES PATENT OFFICE.

EMMETT N. FISCHER, OF BRISTOL, INDIANA.

TROUSERS AND NECKTIE HOLDER.

1,276,513.

Specification of Letters Patent. Patented Aug. 20, 1918.

Application filed November 23, 1917. Serial No. 203,558.

To all whom it may concern:

Be it known that I, EMMETT N. FISCHER, a citizen of the United States, residing at Bristol, in the county of Elkhart and State 5 of Indiana, have invented certain new and useful Improvements in Trouser and Necktie Holders; and I do hereby declare the following to be a full, clear, and exact description of the invention, such as will enable 10 others skilled in the art to which it appertains to make and use the same.

This invention relates to improvements in trousers and necktie holders.

The object of this invention is to improve 15 the construction of holders so as to provide a simple and inexpensive trousers and necktie holder of a single length of material and one which will be cheap and inexpensive to manufacture.

20 A still further object of this invention is to provide a trousers and necktie holder of such a construction that the neckties and trousers not being worn may be suspended upon the holder and kept in place and loss 25 or misplacing of the same prevented.

A still further object of this invention is to provide a device of this character, which will be simple, practical and comparatively inexpensive in construction and one that can 30 be manufactured and sold at a low cost.

With these and other objects in view, the invention consists in the novel combination and arrangement of parts hereinafter more fully described and set forth in the claims 35 hereto appended.

In the drawing

Figure 1 is a perspective view illustrating the trousers and necktie holder as made in accordance with this invention, and

40 Fig. 2 is an end elevation of the same.

Referring to the drawing, the numeral 5 indicates the holder in its entirety and it is constructed of a single length of material such as wire or the like or other material 45 suitable for the purpose. The material is bent back upon itself intermediate its ends to provide a hook 6 and the terminals of the hook are bent laterally in opposite directions to provide the horizontally disposed bars 7. The terminals of the bars 7 are 50 bent downwardly at right angles thereto in a substantially vertical plane to provide end connecting members 8. The terminal of one end connecting member is bent forwardly 55 and disposed in a substantially horizontal plane to provide an end supporting bar 9,

the terminal of the end supporting bar 9 is bent at right angles thereto and in spaced parallel relation with the bars 7 and in a plane below the same, thereby constituting 60 a rack bar 10. The terminal of the rack bar is bent rearwardly to provide a latch 11 and the terminal of the latch is bent in a substantially horizontal plane in spaced parallel relation with the rack bar 10 to provide 65 a clamping bar 12, the terminal of the clamping bar being connected as at 13 to the end connecting bar or supporting bar 9 of the holder.

The other end connecting bar 8 has its 70 terminal looped as at 13' and extended forwardly as at 14 in a plane beyond the bar 9, the bar 14 is then bent back upon itself as at 15 and has its terminal arranged in spaced parallel relation with the bar 14, 75 as at 16 to constitute a keeper, the terminal of the keeper is extended through the loop 13' and extended over to and connected to the bar 9 as at 17 and it is in abutting engagement with the opposing face of the bar 80 12 thus constituting the other clamping member 18 and the clamping members 12 and 18 when moved into engagement with one another are adapted to support a pair of trousers therein, which trousers are designated by the character A in the drawing.

The rack bar 10 is adapted to have arranged thereover the ties designated B, and thus it can be seen that the device may be readily supported in a cupboard or upon a 90 wall or the like and the trousers held in their creases when not being worn.

In use, the rack bar 10 is grasped and the latch 11 is swung from between the keeper bars 14 and 16 respectively. The trousers 95 are arranged in their creases and the cuffs of the trousers are in alignment and the trousers are inverted so as to be inserted between the clamping bars 12 and 18 respectively, then the pressure is applied to the 100 rack bar positioning the latch 11 between the bars 14 and 16 thus clamping the trousers in the position illustrated in Fig. 1 of the drawing.

Having thus described my invention, what 105 I claim is:

1. A trousers and necktie holder formed of a single length of wire bent to provide a supporting hook and frame, clamping members formed integrally with said frame, 110 a supporting rack formed integrally with the clamping members, and means for hold-

ing the clamping members in engagement with each other when carried by the frame.

2. A holder of the class described formed of a single length of wire bent intermediate its ends to provide a hook, the terminals of the hook bent laterally in opposite directions to provide a pair of supporting bars, connecting members formed integrally with the supporting bars, a supporting rack formed integrally with one terminal of one connecting member, a clamping member formed integrally with the terminal of the other connecting member, a pair of clamping bars formed integrally with the rack and keeper.

15 3. A trousers holder and necktie rack formed of a single length of wire bent intermediate its ends to provide a hook, the terminals of the hook bent laterally in opposite directions to provide horizontally disposed supporting bars, the terminals of the bars bent downwardly in a substantially vertical plane to provide connecting members, one of the connecting members bent forwardly and back upon itself in spaced parallel relation to the supporting bars and in a plane below thereof to constitute a rack bar, the rack bar bent rearwardly to provide a latch, the terminal of the latch bent inwardly in spaced parallel relation to the 25 rack bar and connected to the connecting bar to provide a clamping member, and another clamping member formed integrally

with the connecting member in spaced parallel relation with the first named clamping member, said rack bar adapted to facilitate 35 the moving of the clamping bars into and out of engagement with one another, as and for the purpose specified.

4. A holder of the class described consisting of a single length of wire bent intermediate its ends to provide a supporting hook, horizontally disposed supporting bars formed integrally with the terminals of the hook, connecting members formed integrally with the terminals of the supporting bars, supporting bars extending from and formed integrally with the connecting members, a keeper formed integrally with one of the connecting bars, a rack bar formed integrally with the other connecting bar and in spaced parallel relation with the supporting bars in a plane below thereof, and clamping members formed by the latch and rack bar, said clamping members having a catch formed integrally therewith for engagement with the keeper to hold the clamping bars into engagement with one another, as and for the purpose specified.

40 In testimony whereof I affix my signature in presence of two witnesses.

45 EMMETT N. FISCHER.

50 Witnesses:

55 ALICE E. FISCHER,
AUSTIN MENGES.
